UNITED STATES PATENT OFFICE.

JOHN J. WOMPEY, OF DENVER, COLORADO, ASSIGNOR TO THE L. GRAUMAN COMPANY, A CORPORATION OF COLORADO.

LINING STRUCTURE FOR ICE-RECEPTACLES.

1,276,303.

Specification of Letters Patent. Patented Aug. 20, 1918.

Application filed September 5, 1916. Serial No. 118,482.

To all whom it may concern:

Be it known that I, JOHN J. WOMPEY, a citizen of the United States, residing at Denver, in the county of Denver and State of Colorado, have invented certain new and useful Improvements in Lining Structures for Ice-Receptacles, of which the following is a specification.

This invention relates to improvements in soda-fountains, bars, refrigerators and other structures of similar character, which contain a receptacle of copper or other non-corrosive material for the storage of ice and perishable provisions.

My invention is more particularly adapted for use in connection with the ice-cream receptacle of a soda-fountain, its primary object being to provide a lining-structure of steel or other suitable wear-resisting material which protects the copper walls of the receptacle against wear and damage.

It is well known to those versed in the art to which the present invention appertains, that the ice-cream receptacle of a soda-fountain usually shows evidence of leakage long before any other part of the apparatus is affected by wear, the leakage being caused by contact of the ice and the sharp-pointed tools used in breaking the same, with the walls of the receptacle which necessarily must be made of noncorrosive material, such as copper, that is easily punctured, cut or torn.

Another object of my invention resides in providing a hinged cover to protect the rear edge of the ice receptacle while the receptacle is being filled.

This edge is usually made of German silver or other soft metal and inasmuch as it is customary in filling the receptacle to rest the blocks of ice on this edge and while in this position break them into pieces which fit around the ice-cream cans, it is obvious that as a result of the frequent pounding and jarring to which it is subjected, the edge is soon battered and broken.

With the above objects in view, my invention comprises a lining structure preferably made of sheet-steel and composed of sections which fit together at their adjoining edges to conjointly provide a lining which fits snugly within the ice receptacle of the

soda-water fountain or other structure to which the invention is applied.

The lining is constructed so as to completely cover every part of the receptacle in which it is fitted and to this end includes a cage-section which covers the overflow pipe usually extending into the receptacle, and mantle-sections which surround the ice-cream cans placed upon the bottom of the same.

The sections of which the lining is composed while fitted at their adjoining edges to produce substantially water-tight joints, are retained in their relative positions, only by the use of one or two screws which secure one of the sections to the corresponding wall of the receptacle.

The lining may thus be readily installed or removed for cleaning purposes or repairs, without the use of tools other than that required to adjust the screws above referred to, and owing to its extremely simple construction, it can be produced at a very low cost.

The protective covering for the rear edge of the receptacle consists of a strip of steel or other wear-resisting metal which is formed to fit over the edge and is hinged upon the rear-section of the lining to be moved out of the way when the ice-receptacle is closed by means of the lid which covers the same.

An embodiment of my invention is illustrated in the accompanying drawings, in the various views of which like parts are similarly designated, and in which,

Figure 1 represents a plan view of the ice-cream receptacle of a soda-fountain to which my invention is applied,

Fig. 2, a section taken along the line 2—2, Fig. 1,

Fig. 3, a sectional detail view of one of the joints at the corners of the bottom and front sections of the structure,

Fig. 4, a detail view of the front section of the lining,

Fig. 5, a similar view of the bottom section of the same,

Fig. 6, a similar view of the rear section of the structure, and

Figs. 7 and 8 similar views of the end sections thereof, Figs. 4 to 8 inclusive having

been arranged on the drawing with their edges at which they adjoin when assembled, opposite each other,

Fig. 9 represents a section along the line 5 9—9, Fig. 4;

Fig. 10, a section along the line 10—10, Fig. 8, and

Fig. 11, a section along the line 11—11, Fig. 7.

10 Fig. 12 shows an enlarged plan view of the corner of the ice-receptacle at which the overflow pipe is located and the parts of the lining which cover the pipe;

Fig. 13, represents a vertical section along 15 the line 13—13, Fig. 12;

Fig. 14, a section taken along the line 14—14, Fig. 1;

Fig. 15, a horizontal section through the lining in its assembled condition, showing 20 a modified method of joining the edges of its sections;

Fig. 16, a section through one of the corners of the assembled structure showing another modification of the joint at the edges 25 of its sections;

Fig. 17, a section along the line 17—17, Fig. 1, and

Fig. 18, a sectional view showing the strip 34 extending into the receptacle.

30 Referring to the drawings by numerical reference characters, 2 designates the rectangular ice-receptacle of a soda-fountain, the walls of which are composed of sheets of copper or other noncorrosible material.

35 The rear wall 3 of the receptacle is at its upper edge bent outwardly to provide a cover 4 for the jacket formed between said rear wall and the corresponding wall 5 of the fountain structure, to contain a nonconducting material, and the counter 6 of the fountain projects in some instances over the front side of the receptacle as shown in Fig. 17.

40 A pipe 7 provided to receive the overflow 45 of liquid contained in the receptacle, is installed in one of the corners of the same.

The lining structure is composed of a plurality of sections, to-wit;—a bottom section 8, front and rear side sections 9 and 10, end 50 sections 11 and 12, a cage-section 13 which covers the overflow pipe, a cover-section 14 which closes the space between the cage-section and the side and end sections which it adjoins, at the upper edge of the lining, and two mantle sections 15 which are erected 55 upon the bottom-section to protect ice-cream cans 30 placed within the receptacle.

All the sections of the lining structure are made of sheet steel and with the exception of the cage, cover and mantle sections, are designed to fit snugly against the corresponding walls of the ice-receptacle to which the lining is applied.

The bottom-section 8 of the structure, 60 which in practice is supported upon the bot-

tom of the receptacle, is composed of a plate the edges of which are bent upwardly to provide four upright flanges 16 which are beveled at their ends.

The section is furthermore provided with 70 two series of lugs 17 placed at quadrant points of circles to support the cylindrical, perforated mantle sections in an upright position and it is cut away at one of its rear corners, as at 18, to admit the overflow 75 pipe 7.

The front member 9 has at its end edges 80 rectangularly bent flanges 19 and its lower edge is offset to overlap the corresponding flange of the bottom section.

In case the counter of the fountain extends over the front of the ice receptacle as shown in Fig. 17, the front section of the lining has at its upper edge an inwardly turned flange 20 to fit beneath the counter.

The rear section has rectangularly bent flanges 21 at its end edges, and its upper edge is bent slantingly outwardly to provide a flange 22 which fits upon the cover of the jacket hereinbefore referred to.

The lower edge of the rear section is like that of the front section, offset to overlap the corresponding flange of the bottom section.

The two end-sections are offset along their 90 vertical and bottom edges to fit over the adjoining vertical flanges of the front, rear and bottom sections.

The rear section and the end-section at the end of the receptacle at which the overflow 100 pipe is located, have vertical slide ways 23 and 29 to receive the cage-section which is composed of a transversely curved plate perforated for the passage of water and slidably fitted at its longitudinal edges within 105 said ways.

The slide-ways on the two sections are made of one of the hereinabove mentioned flanges at the vertical edges thereof, and angle bars secured in parallel relation to 110 said flanges.

A lip 24 extending beyond the flanged edge of the end-section 11 is provided to extend across the cover 4 of the jacket shown in Fig. 13.

The cover-section 14 of the structure which covers the space between the cage-section and the side and end-sections which it adjoins, consists merely of a plate which rests upon the edges of the section around 120 the pipe and has an opening for the passage of the pipe as best shown in Fig. 13.

A collar 25 may be secured to the pipe as shown in Fig. 13 to provide an additional support for the cover-section.

To assemble the sections of which my lining structure is composed, the bottom section is placed upon the bottom of the ice-receptacle, the side sections are placed against the rear and front surfaces of the 130

receptacle and upon the bottom section with their lower edges in lapping relation to the flanges at the corresponding edges of the same.

5 The end sections are placed against the end-surfaces of the receptacle with their offset edges in lapping relation to the corresponding edges of the bottom and side sections, the cage section is slid into the 10 ways on the sections 10 and 11, the cover-section is placed around the overflow pipe and upon the edges of the cage-section and the sections with which the latter is connected, and the entire structure is secured 15 against displacement by two or more screws 26 inserted through registering openings in the slanting flange 22 at the upper edge of the rear side section and the cover portion 4 of the jacket upon which said flange is 20 fitted.

The perforated mantle sections 15 are placed against the series of lugs 17 on the bottom section to receive the ice-cream cans and protect them from contact with the ice.

25 The flanges at the ends of the bottom-section and the front section, abut at their beveled extremities as shown in Fig. 3.

The protective covering provided to cover the rear edge of the ice-receptacle during 30 the process of filling the same, consists of a strip 34 of steel or other wear-resisting metal which is hinged as at 35 upon the flange 22 of the rear section 10 of the lining and which is formed to fit over the rear 35 edge of the receptacle when the lid which normally covers the same, is lifted.

When the receptacle is closed the strip 34 extends within the same as shown in Fig. 18 and it must be moved to its position upon 40 the edge of the receptacle before the latter can be filled with ice. Before replacing the lid, the covering must necessarily be replaced in its former position.

In the modification shown in Fig. 15, the 45 offset edges of the end-section of the lining structure, are placed in slide-ways produced by flanges of the side sections, and angle bars 27 secured in parallel relation to said flanges, and in the modified form illustrated 50 in Fig. 16, the flanges on the sections are formed by separate angle-bars 28 riveted along the edges of the same.

It will be readily seen from the above 55 description that the lining structure fully and adequately protects the walls of the ice receptacle, the ice-cream cans within the same, and the overflow pipe, from danger by contact of the ice or the sharp-pointed tools used to break the same, that the structure 60 is readily installed or knocked down and removed, and that the parts are so constructed that in case of wear, any section may be instantly replaced by a new one of similar construction.

65 In case it is desired to pack ice around

the mantle of one of the ice-cream cans, exclusive of that which surrounds the other, the receptacle 2 may be divided into two compartments by a transverse partition which in the construction shown in the drawings is provided by a plate 32 which is held in place by angle-bars 31 riveted upon the side plates 9 and 10.

Having thus described my invention what I claim and desire to secure by Letters-Pat- 75 ent is:

1. A lining-structure for ice-receptacles of the character described, a cage-section fitted across a corner thereof to cover an overflow pipe within a receptacle to which the structure is applied, and a cover section to cover the space around the overflow-pipe limited by the cage section. 80

2. A lining-structure for ice-receptacles composed of sections adapted to cover the 85 surfaces of the receptacle and separably fitted together, and a covering hinged on one of said sections and adapted to cover the upper edge of the adjoining wall of the receptacle. 90

3. The combination with an ice-receptacle of the character described, including a jacketed wall, of a lining structure composed of sections adapted to cover the surfaces of the receptacle and separately fitted together 95 at their adjoining edges, one of said sections having a flange covering the top of said jacket, and a covering hinged on said flange and adapted to cover the upper edge of said wall of the receptacle. 100

4. The combination with the ice-receptacle of a soda-fountain or refrigerator, of a collapsible lining-structure composed of sections which cover the bottom and sides thereof, a section which divides the receptacle into separated compartments, and means for securing the structure in the receptacle, said sections being loosely interlocked at their adjoining edges to be separately removable from the receptacle. 105

5. The combination with an ice-receptacle of a soda-fountain or refrigerator, of a collapsible lining structure composed of loosely interlocked sections covering the sides and bottom of the receptacle and separately removable therefrom, one of said sections having a flange covering the upper edge of the adjoining wall of the receptacle, and means which by fastening said flange to said wall, secure the entire structure in place. 115

6. A collapsible lining structure for the ice receptacles of soda fountains or refrigerators, composed of sections adapted to cover the bottom and sides of an ice-receptacle and means for securing said structure 125 in the receptacle, the several sections being loosely interlocked at their adjoining edges to be separately removable from the receptacle to which the structure is applied.

7. A collapsible structure for ice-recepta- 130

cles of soda-fountains or refrigerators, comprising loosely interlocked lining-sections adapted to cover the bottom and sides of an ice-receptacle, means for securing said sections in the receptacle, and a cage-section adapted to cover an overflow pipe in a corner of the same, said cage-section and adjoining lining-sections having coöperative means for

holding the one in its operative position with relation to the others. 10

In testimony whereof I have affixed my signature in presence of two witnesses.

JOHN J. WOMPEY.
